ROTARY INTAGLIO PRINTING PRESS

Curtis S. Crafts, Oak Park, Ill., assignor to The
Goss Printing Press Company, Chicago, Ill., a
corporation of Illinois

Application January 6, 1936, Serial No. 57,683

19 Claims. (Cl. 101—157)

The invention relates to new and useful improvements in inking mechanisms for rotary intaglio presses and more particularly to such improvements in the means for mounting and operating the doctor blade.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a fragmentary top plan, looking from line 1—1 of Fig. 3, of a mechanism embodying the invention;

Fig. 2 is a fragmentary elevation of the middle part of Fig. 1;

Fig. 3 is a vertical section on line 3—3 of Fig. 1; and

Fig. 4 is a vertical section on line 4—4 of Fig. 1.

Objects of the invention are to provide a novel mechanism which is simple, of relatively few parts, sturdy, reliable and efficient in operation; to provide such a mechanism which causes the doctor blade to exert a finely regulable resilient pressure on the design cylinder, and which will move the blade into and out of operative relation with the cylinder without disturbing the previously adjusted resilient action of the blade with the cylinder. Also to provide a doctor blade carrier having parts reciprocable together to reciprocate the blade along the face of the cylinder, said parts being relatively angularly movable under resilient pressure exerted between them to cause resilient pressure of the reciprocating doctor blade on the design cylinder; and to further provide that said parts are also angularly relatively movable to move the doctor blade into and out of operative relation with the design cylinder, this on and off movement being effected without disturbing a previously effected regulation of the blade pressure on the cylinder. Also to provide preferred mechanisms for carrying out the above-stated objects together with provisions for accurate and reliable positioning of

parts, for easy and economical manufacture and assembling, and for quick and easy operation and manipulation of parts. Other objects of the invention will appear in connection with the detail description of the present preferred embodiment of my invention.

Referring now in detail to the embodiment of the invention illustrated by way of example in the accompanying drawings, an intaglio printing couple comprising a design cylinder 1 and an impression cylinder 2 which are suitably journaled in the press frame 3. A supporting structure for the doctor blade carrying, regulating and actuating mechanism is provided, and as shown, it is adapted for use with the closed fountain type of intaglio press, and with other types of intaglio presses as well. The structure as shown is mounted on the frame 3 of the press and also on the top of the ink fountain structure 4. As shown, it has an inner continuous, generally vertically disposed curved wall 9, extending across between the side frames, and adapted to constitute a part of the closure of a sealed ink fountain, although so far as concerns many features of the invention this wall, or large portions of it, may be omitted.

Integral with or fixed to the ends of the wall member 9, and abutting against the side frame members of the press, are end plates 10 of this supporting structure for the doctor blade mechanism, and the entire structure is made vertically adjustable or positionable on the press frame. With this end in view there are vertical, outwardly-extending ribs 11 formed on the vertical edges of the end plates 10, these ribs projecting within bracket plates 12, which are bolted on to the side frames 3 of the press. Bolts 13 project through elongated slots 14 formed in the bracket plates 12, the bolts being screw-threaded into the frame 9, and serve to clamp the supporting frame 9, 10 in any desired vertical position within the range of the slots. Similar supporting means are provided at the bottom end of the structure, where bolts 15 project through elongated slots 16 formed in the upper part of the fountain wall 4, and are screw-threaded into the bottom part of the end plates 10, in like manner to the bolts 13 already described. This affords a vertical adjustment of the entire doctor blade mechanism and its supporting frame on the frame of the press and relatively to the design cylinder.

Referring now to the mechanism for supporting and reciprocating the doctor blade, a rod 23 is mounted in internal recesses in blocks or pedestals 24, located at either side of the press, and

which are bolted on to a top plate 25 of the supporting structure 9, 10 already described. The rod 23 is both rotatable and longitudinally reciprocable in its supports 24. The doctor blade 5 supporting structure is mounted on and supported by the rod 23, and is fixed thereto so as to reciprocate therewith and have common angular motion with the rod. This reciprocable doctor blade support comprises a plurality of spaced-apart collars 28 which encircle the rod 23 and are fixed thereto by pins 29, so that they move together. Integral with and projecting forwardly from the respective collars 28 are members 30 which at their other ends are also integral with a seat or rail 31 which extends continuously across the width of the press and throughout the length of the doctor blade and the design cylinder (Fig. 1). On its upper side this rail 31 is recessed longitudinally to constitute a seat for the doctor blade carrier proper. This doctor blade carrier comprises two flat metal plates 32 and 33, longer than the design cylinder, between which the resilient doctor blade 34 is firmly held, the plates being fastened together tightly with the previously tensioned doctor blade firmly held between them, and projecting a considerable distance beyond their side edges on the side toward the design cylinder of the press. As shown, the lower plate 32 projects outwardly beyond the plate 33, as is best seen in Fig. 3. The embodied means for holding the doctor blade and its carrier, the supporting plates 32 and 33 in position on the seat of the carrier comprises a plurality of spaced-apart clamping fingers 39 which bear on the top of the plate 33. Screw-threaded pins 40 are fixed in the top of the carrier 31 and project through openings in the corresponding clamping fingers 39, and nuts 41 hold the clamping fingers firmly in position and exerting powerful pressure upon the plate 33 of the doctor blade carrier.

Means are provided for accurately positioning the doctor blade and its supporting plates 32 and 33 upon the carrier 31, which effects the positioning of the doctor blade with respect to the design cylinder. In said means, (Fig. 1) a screw rod 47 is journaled in the vertical flange or rear part 48 of the carrier 31, and is held from longitudinal movement in flange 48 by a collar 49 on the opposite side of the flange. Screw rod 47 is threaded into the rear side of plate 33. Cooperating with screw rod 47 is a bolt 50, which is screw-threaded into the flange 48, and its end abuts against the plate 33, the bolt being supplied with a lock nut 51. The two bolts work against each other and serve to accurately position the doctor blade and its carrier and to hold them firmly in position. A suitable counterbalance for the blade carrier about rod 23 is provided, and as shown an arm 43 is fixed to rod 23 and projecting rearwardly therefrom.

Means are provided for transversely flexing the doctor blade and one of the members employed for this purpose is a plate 57, which rests upon a forwardly and downwardly beveled face formed along the top and at the front edge of the plate 33, and is secured thereto by bolts 58. This plate flexes the doctor blade 34 from the edge of plate 32 outwardly, and transversely along its entire length, down toward the surface of the design cylinder. Cooperating with the foregoing mechanism is a resilient backing blade 59, which is seated firmly between two clamping plates 60 and 61, which are fastened together, and are both fastened to the upper outside edge 62 of the

wall 9. Preferably there is a second shorter resilient blade 63 contacting with and backing the backing blade 59, this structure forming an ink seal to prevent ink passing back into the mechanism. The blade 59 is strongly flexed and its outer edge presses resiliently against the under side of the doctor blade 34 throughout its length, and holds it powerfully yet resiliently against the plate 57, while permitting resilient yielding action of the desired intensity. 10

Means are provided for exerting a finely regulable resilient pressure of the doctor blade 34 against the design cylinder, and in the embodied form thereof this means operates through the blade carrier, and as embodied, a U-shaped frame 71 is fastened at both its ends by bolts 72 to seats on the rear sides of the two central collars 28, and the frame is thus fastened to the longitudinally reciprocable and angularly movable rod 23 and the blade carrier supported by the rod. 20 There is a U-shaped or yoke-like frame 74 which has at either end internally apertured bosses or collars 75 and 76, which collars encircle rod 23, but are not fastened thereto. These collars 75 and 76 make a tight fit against the outside ends 25 of the central collars 28, for a purpose later to be described. The frame 74 extends outwardly and rearwardly from the rod 23 just beneath the frame 71 previously described, and has longitudinal movement with the frame 71 but is held 30 against angular movement about rod 23. For this purpose, centrally of the median portion of the frame 74 is formed a collar 79, which encircles and slides along a fixed guide rod 80, which is mounted on the upward extension 81 of 35 the central rear part of frame 9, 10. Means are mounted between these two frames 71 and 74 for effecting the desired resilient pressure of the doctor blade upon the design cylinder, while permitting the doctor blade to be moved toward and 40 away from the design cylinder, and thus into and out of operative relation with the cylinder, without disturbing the adjustment of the resilient pressure. In the embodied form the frame 74 reciprocates with the rod 23 but is restrained 45 from angular motion, while the frame 71 also reciprocates with the rod 23 and is pinned to the rod so that they move angularly together, and the regulable resilient pressure is exerted between 50 the two frames. 50

Referring now in detail to the resilient pressure exerting means, a nut 83 has a pivotal mounting 84 in an opening in the central part of the cross reach of the frame 74. Screw-threaded in the nut 83 is a screw rod 85, having a nut 86 screwed 55 onto and fastened to its outer end to function as a stop against the nut 83, to limit the movement of the frame 71 away from the frame 74 under the action of the spring means later described. Fixed medianly on screw rod 85 is a collar 89 and 60 mounted on the screw rod just above collar 89 is a thrust ball-bearing 91, held in place by a collar 92 fixed to the screw rod on the opposite side of the bearing. Bearing against the inner face of the thrust bearing is a spiral compression spring 93, the other end of the spring pressing against the end of a hollow cylindrical member 94, having at its outer end a hand-wheel 95. The cylindrical member 94 has an external screw-thread, which is threaded into an internally 70 screw-threaded hollow member 96, pivotally mounted at 97 in an opening in the central part of the cross reach of the frame 71. Screw rod 85 is provided at its upper end with a crank handle 98. A lock nut 99 is provided at the nut 75

83 and a lock nut 100 is provided at the top of the member 96.

As the frame 74 is held against angular movement by reason of its two slidable mountings on the rod 23 and the rod 80, while frame 71 is free to move angularly, the pressure from the spring 93 is exerted upon the doctor blade 34 against the design cylinder 1, and by rotating the hand-wheel 95, the desired degree of spring pressure 5 may be exerted by the doctor blade upon the cylinder. When it is desired to move the doctor blade away from the design cylinder, the handle 98 is turned, the lock nut 99 having been previously loosened. Rod 85 is thus moved longitudinally through nut 83 and frame 71 is swung 10 downward, and the doctor blade carrier 31 is swung upwardly, carrying the doctor blade away from the design cylinder. When the doctor blade is to be moved backwardly, handle 98 is turned in the opposite direction, screw rod 85 moves upwardly through nut 83 until fixed nut 86 15 engages 83, at which time the doctor blade is pressing on the design cylinder with the same amount of resilient pressure as before and as set 20 and determined by means of the hand-wheel 95.

The embodied form of means for reciprocating the doctor blade along the design cylinder comprises a barrel cam 106, fixed on a shaft 107, journaled in the frame. A cam roller 108 running in the groove of cam 106 is mounted on one 30 end of a lever 109, which is pivotally mounted on a pin 110, supported on the frame structure. At its other end lever 109 is pivotally connected at 112 to a connecting rod 113, which rod is pivotally connected at its other end by lug 114 to the yoke 74. As previously stated, the inside faces of the collars 75 and 76 of yoke 74 fit tightly against the outside faces of the middle collars 28, which are pinned to the shaft 23. Thus the entire structure described, with the doctor blade carrier and the doctor blade, are reciprocated together in the bearings 24 of the shaft 23, causing the doctor blade to reciprocate on the face of the design cylinder.

45 The invention in its broader aspects is not limited to the specific mechanisms shown and described but departures may be made therefrom within the scope of the accompanying claims without departing from the principles of the invention and without sacrificing its chief 50 advantages.

What I claim is:

1. A rotary intaglio inking mechanism including in combination a longitudinally reciprocable 55 blade carrier, a doctor blade mounted on said carrier to reciprocate on the design cylinder, means mounted on said carrier for resiliently pressing the doctor blade against the design cylinder, means for regulating the pressure of the doctor blade on the cylinder, and means for moving the doctor blade into and out of operative relation with the design cylinder without disturbing the setting of said pressure regulating means.

2. A rotary intaglio inking mechanism including in combination a longitudinally reciprocable 60 blade carrier, a doctor blade mounted on said carrier to reciprocate on the design cylinder, means mounted on the carrier for pressing the blade on the design cylinder and for regulating said pressure, said means including a spring and means for regulating the pressure of said spring on the blade.

3. A rotary intaglio inking mechanism including in combination a longitudinally reciprocable 65 blade carrier, a doctor blade mounted on said

carrier to reciprocate on the design cylinder, means mounted on the carrier for pressing the blade on the design cylinder and for regulating said pressure, said means including a spring and screw operated means for regulating the pressure 5 of said spring on the blade.

4. A rotary intaglio inking mechanism including in combination a longitudinally reciprocable blade carrier, a doctor blade mounted on said carrier to reciprocate on the design cylinder, a member on said carrier connected to move said doctor blade against the design cylinder, a spring mounted on said carrier and pressing against said member and means for regulating the pressure of said spring. 10

5. A rotary intaglio inking mechanism including in combination an angularly movable doctor blade, means for reciprocating the blade along the design cylinder, means for resiliently pressing the blade against the cylinder and for regulating said pressure, including two members reciprocating 15 with the blade, one of said members being angularly movable with the blade, and a device for exerting regulable resilient pressure between said two members in an angular direction. 20

6. A rotary intaglio inking mechanism including in combination an angularly movable doctor blade, means for reciprocating the blade along the design cylinder, means for resiliently pressing the blade against the cylinder and for regulating 25 said pressure, including two members reciprocating with the blade, one of said members being angularly movable with the blade, and a device for exerting regulable resilient pressure between said two members in an angular direction, 30 and means for effecting relative angular movement between said members to move the doctor blade into and out of operative relation with the design cylinder. 35

7. A rotary intaglio inking mechanism including in combination an angularly movable doctor blade, means for reciprocating the blade along the design cylinder, means for angularly moving the blade including a spring pressing the blade toward the cylinder and a screw acting on the 40 spring to regulate the spring pressure.

8. A rotary intaglio inking mechanism including in combination an angularly movable doctor blade and a member mounted on opposite sides of an axis to move together, an arm restrained from 45 angular movement with said blade and member, a screw rod connecting said arm and member, the screw rod having screw thread connection with one of said members and a spring interposed in the connections between the screw rod 50 and the other of said members. 55

9. A rotary intaglio inking mechanism including in combination an angularly movable doctor blade and a member mounted on opposite sides of an axis to move together, an arm restrained from 60 angular movement with said blade and member, a screw rod connecting said arm and member, the screw rod having screw thread connection with one of said members and a spring interposed in the connections between the screw rod 65 and the other of said members and a screw threaded member for regulating the pressure of said spring.

10. A rotary intaglio inking mechanism including in combination an angularly movable 70 doctor blade and a member mounted on opposite sides of an axis to move together, an arm restrained from angular movement with said blade and member, a nut carried by one of said members, a screw rod threaded in the nut, a spring 75

- pressing on the screw rod, a screw mounted on the other of said members and adapted to vary the pressure on said spring, and means for turning the screw rod.
- 5 11. A rotary intaglio inking mechanism including in combination a reciprocable and angularly movable rod, a doctor blade carrier fixed to and projecting from said rod, a doctor blade mounted on said carrier, an arm fixed to and extending 10 from said rod, an arm loosely mounted on said rod but reciprocating with the rod, means for exerting regulable pressure between said arms including a spring and a screw for regulating the spring pressure.
- 15 12. A rotary intaglio inking mechanism including in combination a fixed frame above the ink fountain, a doctor blade carrier mounted on said frame and having reciprocatory and angular movement relative to the frame, said carrier being 20 angularly movable to carry the doctor blade into and out of operative relation to the design cylinder, and means for placing variable resilient pressure on said carrier to regulate the pressure of the doctor blade on the design cylinder.
- 25 13. A rotary intaglio inking mechanism including in combination a fixed frame above the ink fountain, a doctor blade carrier mounted on said frame and having reciprocatory and angular movement relatively thereto, and means for 30 angularly moving said carrier to regulate the pressure of the doctor blade on the design cylinder, said means including a spring and a screw for regulating the pressure of the spring.
- 35 14. A rotary intaglio inking mechanism including in combination a longitudinally reciprocable rod, a doctor blade carrier fixed to the rod, a doctor blade on the carrier, a fixed guide parallel to said rod, a yoke mounted to reciprocate on said guide and mounted on said rod to reciprocate with the rod, means for exerting resilient 40 pressure between the yoke and the doctor blade carrier, and means for regulating the resilient pressure.
- 45 15. A rotary intaglio inking mechanism including in combination a longitudinally reciprocable rod, a doctor blade carrier fixed to the rod, a doctor blade on the carrier, a fixed guide parallel to said rod, a yoke mounted to reciprocate on said guide and mounted on said rod to reciprocate with the rod, means for exerting resilient 50 pressure between the yoke and the doctor blade carrier, including a screw rod between the yoke and carrier and having screw threaded connection with one end and a spring and screw threaded connection with the other.
- 55 16. A rotary intaglio inking mechanism including in combination a longitudinally reciprocable rod, a plurality of supports therefor, means for reciprocating the rod, a doctor blade carrier fixed to the rod, a doctor blade on the
- carrier, a fixed guide parallel to said rod, a yoke mounted to reciprocate on said guide and mounted on said rod to reciprocate with the rod, means for exerting resilient pressure between the yoke and the doctor blade carrier, means for regulating the resilient pressure, means for moving the blade carrier relatively to the yoke to move the blade into and out of operative relation to the design cylinder without disturbing the pressure regulation on the blade, and means for reciprocating the rod, the yoke and blade carrier together to move the blade along the design cylinder. 5
17. A rotary intaglio inking mechanism including in combination a longitudinally reciprocable rod, supporting means therefor, means for reciprocating the rod on its supporting means, a doctor blade carrier fixed to the rod, a doctor blade on the carrier, a fixed guide parallel to said rod, a pressure exerting member fixed to said rod 20 and extending therefrom on the opposite side from the blade carrier, a yoke mounted to reciprocate on said guide and mounted on said rod to reciprocate with the rod, a spring exerting pressure between the yoke and said pressure exerting member and causing the doctor blade to press on the cylinder, screw means for regulating said pressure, and means for effecting relative movement of said yoke and said pressure exerting member to lift the doctor blade from the cylinder and to restore it to position against the cylinder without disturbing the previously adjusted spring pressure regulation. 25
18. A rotary intaglio inking mechanism including in combination a longitudinally reciprocable 30 rod, a plurality of supports therefor, means for reciprocating the rod on its supports, a doctor blade carrier fixed to the rod, a doctor blade on the carrier, a fixed guide parallel to said rod, a pressure exerting member fixed to said rod and 35 extending therefrom on the opposite side from the blade carrier, a yoke mounted to reciprocate on said guide and mounted on said rod to reciprocate with the rod, a nut mounted on the yoke, a screw rod threaded in the nut, a stop on the end 40 of the screw rod for engaging the nut to stop the rod, a collar on the screw rod, a thrust bearing abutting the collar, a spring encircling the screw rod and a holder for the spring screw threaded onto said pressure exerting member for regulating the tension on the spring and thereby the 45 spring pressure of the doctor blade on its cylinder. 50
19. In a doctor blade mechanism, a reciprocable blade carrier, a resilient doctor blade mounted in the carrier, a rigid plate mounted on the blade carrier and pressing the doctor blade to flex it toward the design cylinder, and a stationary resilient blade pressing the doctor blade against said rigid plate. 55

CURTIS S. CRAFTS. 60
